UNITED STATES PATENT OFFICE.

JOHN MROSKO, OF BELLEVILLE, ILLINOIS.

SUBMARINE CUTTER.

1,258,135.

Specification of Letters Patent.

Patented Mar. 5, 1918.

Application filed September 1, 1917. Serial No. 189,299.

To all whom it may concern:

Be it known that I, JOHN MROSKO, a subject of the Emperor of Austria, resident of Belleville, county of St. Clair, and State of Illinois, have invented certain new and useful Improvements in Submarine Cutters, of which the following is a specification.

This invention relates to improvements in submarine vessels and has as its special object the provision of means whereby, should the vessel carrying the same come into intimate contact with netting, chains or like entanglements, to sever the same, permitting the submarine to pass through. A further object is to provide such devices in forms which can be readily applied to submarines as constructed without entailing material change in their structure.

These and other like objects are attained by the novel construction and combination of parts hereafter described and shown in the accompanying drawings, forming a material part of this specification and in which—

Figure 1 is a side elevational view showing the application of the invention to a submarine of conventional type.

Fig. 2 is an enlarged fragmental vertical sectional view of the same.

Fig. 3 is a diagrammatic view indicating the automatic starting bar.

Fig. 4 is a front elevation of the vessel indicating the manner of attaching the cutting elements, and

Fig. 5 is an enlarged fragmental transverse sectional view, taken on line 5—5 of Fig. 4.

In the drawings, the numeral 10 indicates a conventional type of submersible vessel having attached at the bow or front end thereof, a plurality of rigid brackets 11, directed obliquely outward, other brackets 12 extending downwardly, the latter having engaged at their outermost ends, plates 14 formed with serrations 15, the same having beveled edges acting in the manner of shears in connection with the similarly formed beveled teeth 17 of an inner plate 16, mounted to slide longitudinally of the plates 14.

Similar plates 20 and 22 are carried parallel to the bottom plates on the upper portion of the vessel, these plates extending outward in the same manner, while disposed at the sides of the vessel, supported by brackets 11 and other suitable securing means, are other similar plates 24 engaged

with plates 25, the latter of which operate vertically, being guided by the slots 26 and rivets 27 so as to work in close proximity when in operation.

The movable horizontally disposed plates 16 and 22, have set in their inner surfaces rigid pins 28, engaged with which are links 30, the same being secured at their opposite ends to rings 31 containing eccentrics 32, the latter of which are rigidly engaged upon the extreme outer end of shafts 33, disposed vertically near the center of the bow of the boat, other shafts 34, being arranged horizontally and operating the eccentrics at 70 sides of the vessel as can best be seen in Fig. 4.

All of the several shafts have fixed upon their inner ends bevel gears 35, meshing with a central driving gear 36, which extends through the bow of the boat and is attached to the shaft 38 of an electric motor 40 carried on board the boat, and to which current is conveyed by the wires 41 and 42 from a switch 43, to which lead the wires 44 and 45, from a source of electrical energy, as the battery 46, on board the boat.

The switch 43 is provided with a blade 48, the extending lever handle 49, of which is engaged with the collar 50, on sliding bar 51, which extends through the bow of the boat 10, to some distance beyond the cutting blades and is engaged with a vertical bar 52 which, upon coming in contact to any article offering resistance, causes the shaft 51 to move inwardly, thereby closing the switch and automatically causing current to be conveyed to the motor 40 which, through its connections, cause all of the several shear plates to be put in operation and the plates being arranged in the manner indicated, rapidly clear away any entanglement by severing the wire, ropes, etc., of which they are composed, thereby permitting the vessel to pass through the opening, and it is to be noted that the side plates 24 and 25 are extended to such height above the deck of the vessel as to effect a passage for the superstructure as it is forced forward by the momentum or propelling mechanism of the vessel.

Having thus described my invention what I claim as new and desire to secure by Letters Patent, is—

1. In a cutting device for submarines, the combination of a pair of vertical plates rigidly disposed upon each side of the vessel,

another pair of horizontal plates disposed at the keel and upper deck thereof, all of said plates being at extreme end of the vessel, angularly projecting teeth adapted to act 5 as shears formed upon all of the front edges of said plates and means for transmitting motion to the innermost of said plates whereby said teeth are caused to move reciprocatively with respect to the teeth upon 10 the edges of said fixed plates.

2. In a cutting device for submarines, the combination with a plurality of fixed plates arranged to envelop the extreme front end

of the vessel, a second series of plates slidably engaged with the first named plates, 15 extending shear teeth formed with the front edges of all of said plates, means for moving the second series of said plates reciprocatively with respect to said fixed plates, a contactible element slidably arranged in the 20 hull of the vessel in advance of said plates and means combined therewith, whereby said slidable plates are set in operation.

In testimony whereof I have affixed my signature.

JOHN MROSKO.

Copies of this patent may be obtained for five cents each, by addressing the "Commissioner of Patents, Washington, D. C."
